UNITED STATES PATENT OFFICE.

HOWARD P. NICHOLS, OF READING, MASSACHUSETTS.

BURNISHING-MACHINE.

SPECIFICATION forming part of Letters Patent No. 230,430, dated July 27, 1880.

Application filed June 2, 1880. (No model.)

To all whom it may concern:

Be it known that I, HOWARD P. NICHOLS, a citizen of the United States, residing at Reading, county of Middlesex, State of Massachusetts, have invented certain Improvements in Burnishing-Machines; and I do hereby declare the following to be a full, clear, and exact description of the invention, such as will enable others skilled in the art to which it applies to make and use the same.

This invention relates to machines for burnishing or polishing the edges of heels or soles of boots and shoes in which the burnishing agent is a rotary wheel or disk.

15 My invention is directed to a convenient and effective means of imparting heat to the burnishing-tool without making use of a gas-jet or lamp; and it consists in the combination and arrangement, for this purpose, of the mechanical devices hereinafter described.

The drawings accompanying this specification represent, in Figures 1 and 2, vertical sections of a machine containing my improvements, while Fig. 3 is an end elevation of the 25 same.

In said drawings the frame of the machine is shown at A as composed, in the present instance, of a vertical column or pedestal, B, bearing upon its upper end oppositely-disposed 30 curved arms C C, the upper or outer ends of which constitute bearings for the journals of a horizontal shaft, D, one extremity of which carries a driving-pulley, by which it is put in rotation.

35 Upon the center of the shaft D is mounted and fixed a pair of circular disks or wheels, E E, each having a periphery of a form corresponding to the form of the edge of a boot sole or heel, as the case may be, and the inner 40 edges of these peripheries are let slightly into an annular opening, F, in an upright ring-shaped standard, G, erected upon the top of the column B, the periphery of this standard G constituting a bearing for the tread of the 45 boot heel or sole, the object in introducing the edges of the rotary wheels into the opening being to prevent the unfinished appearance to the corner of the heel or sole which would

result if the edges of the wheels were outside of the standard.

The periphery of each wheel E E overhangs the central body-portion, a, upon the inside, as shown in the drawings, thereby providing an intermediate annular chamber, b, and within this chamber I place a circular annular disk 55 or ring, H, of metal or other suitable material, of a diameter somewhat less than that of the inclosure b, the periphery c of the ring operating, with the conjoint inner peripheries, d d, of the two wheels E E upon one side, to produce 60 heat by friction, as hereinafter stated.

A screw, e, is screwed through one side of the ring-standard G, and so as to abut at its inner end against the periphery of the ring H. By turning the screw in one direction— 65 that is, inward—a sufficient distance the opposite edge of the ring H is crowded against the inner peripheries of the burnishing-wheels E E, the friction thus engendered serving to impart to such wheels the degree of heat which 70 is requisite to obtain the desired burnished surface.

Should the burnishing-tools become unduly hot the screw is to be withdrawn until the ring is removed from pressure-contact with 75 the wheels, when the temperature of the wheels will be reduced, and vice versa.

In order to ascertain the degree of heat of the burnishing-wheels I employ a thermometer, which is secured to an adjacent part of 80 the machine-frame—for instance, a post, f, erected upon the top of the column B—and with its lower end and bulb entering the chamber surrounding the peripheries of the 85 wheels E E.

As the heat imparted to the burnishing-wheels will be radiated to a considerable extent from the latter into the inclosure, and it will be an easy matter to ascertain the average difference in temperature between such inclosure and the rings, the temperature of the latter can be easily determined by ascertaining that of the former, and the thermometer becomes available for this purpose.

I claim—

1. The two burnishing-wheels and their 95

shaft, in combination with the friction - ring contained within and between said wheels, and means, substantially as described, for varying or adjusting the pressure of said ring against

5 said wheels.

2. The combination of the two wheels E, shaft D, ring-standard G, friction-ring H, with- in said wheels, and means, substantially as de-

scribed, for varying the pressure of said ring against said wheels.

In testimony whereof I affix my signature in presence of two witnesses.

HOWARD P. NICHOLS.
